(57) **CLAIM**

We claim the ornamental design for a drill bit, as shown and described.

DESCRIPTION

The file of this patent document contains at least one drawing executed in color. Copies of this patent document with color drawings will be provided by the United States Patent and Trademark Office upon request and payment of the necessary fee.

FIG. 1 is a perspective view of a drill bit according to one embodiment.

FIG. 2 is a first side view of the drill bit of FIG. 1.

FIG. 3 is a second side view of the drill bit of FIG. 1.

FIG. 4 is a third side view of the drill bit of FIG. 1.

FIG. 5 is a fourth side view of the drill bit of FIG. 1.

FIG. 6 is a first end view of the drill bit of FIG. 1; and,

FIG. 7 is a second end view of the drill bit of FIG. 1.

With respect to FIGS. 1-7, color is considered to be an integral part of the disclosed and claimed design.
